J. Bass Avery, Attorney:

UNITED STATES PATENT OFFICE.

DUDLEY H. GILGES, OF BALDWIN, KANSAS.

LACE-CUTTING IMPLEMENT.

974,766.

Specification of Letters Patent.

Patented Nov. 1, 1910.

Application filed September 3, 1909. Serial No. 516,013.

To all whom it may concern:

Be it known that I, DUDLEY H. GILGES, citizen of the United States, residing at Baldwin, in the county of Douglas and State of Kansas, have invented certain new and useful Improvements in Lace-Cutting Implements, of which the following is a specification.

My invention relates to a tool designed for use in cutting belt laces from a strip of leather, the object of the invention being to provide an implement of the character above referred to which shall be provided with an easily adjustable gage whereby the width of the thong or lacing so cut may be kept uniform throughout its whole extent, the gage being adjustable to permit laces of various widths to be cut.

For a full understanding of the invention and the merits thereof, and to acquire a knowledge of the details of construction, reference is to be had to the following description and accompanying drawings, in which:

25 Figure 1 is a plan view of my improved combination tool; Fig. 2 is a side elevation thereof; Fig. 3 is an enlarged transverse section on the line 3—3 of Fig. 1; Fig. 4 is an enlarged view in elevation, of a fragment of the wrench, showing a face view of the lace-cutting knife; Fig. 5 is a perspective view 30 of the combination tool with the awls unfolded; Fig. 6 is a perspective view showing the various elements of the lace cutter 35 assembled; Fig. 7 is a face view of the swaging awl; Fig. 8 is a transverse section on the line 8—8 of Fig. 7; and, Fig. 9 is a transverse section on the line 9—9 of Fig. 5.

Corresponding and like parts are referred 40 to in the following description and indicated in all the views of the drawings by the same reference characters.

Referring to these figures, 2 designates the opposed handles of a pair of pliers, the jaws of which are designated 3. These pliers are pivoted to each other by a bolt 4 having thereon the clamping nut 5. The contacting faces of the two sections of the pliers are correspondingly recessed to fit 50 each other, as is usual in pliers of this character, so that the jaws shall be in alinement with each other. The inside faces of the jaws are cut away and formed with teeth, as at 6, to form the toothed jaws of an alligator wrench. The two members or sections of the pliers are provided with the

corresponding slots 7 and 8 on opposite sides thereof, the slot of one member of the pliers being movable across the slot of the other member of the pliers when the jaws are closed. In other words, when the jaws are closed, the slots of the two plier sections or members are out of alinement with each other. These slots or notches form jaws for cutting wire. So far I have described 65 a construction which is common to a large number of pliers.

It is necessary in the operation of relacing belts or forming holes into which the laces may be placed, to use a number of different awls or perforators. As a means of attaching these awls to the pair of pliers and yet so placing them as not to interfere with the ordinary use of the implement, I attach these several awls or perforators to the handles 2 of the implement, as shown in Figs. 1 and 5. In these figures, 10 designates a thong or lacing awl whose sides are slightly concave, the awl being perforated at a number of points along its length. The broad end of the awl is attached to the extremity of one of the handles 2 by means of a pivot screw 11 which passes through the end of the handle, passes through the butt end of the awl, and is provided at its extremity 75 with the head 12 and washer 13 which bear against a bowed spring 14, the ends of the bowed spring bearing upon the inside face of the awl, and one end of the spring having a tooth which projects into a hole therein. 80 By tightening upon the screw 12, the spring will of course be placed under tension and will grip the awl and hold it in its set position. The spring of course is set at such high tension that when the awl is turned up 85 inside the handle 2, the spring will hold it against any accidental movement. The swaging awl and leather punch is designated 90 by the numeral 19. This awl has a relatively thin blade, slightly concavo-convex laterally, having a very sharp point. The butt end of the awl is held to one of the handles 2 by means of a screw pivot 15 having a head 16, and washer 17, and bearing against the bowed spring 18 of the same character 95 as the spring 14 and operating to the same end. The butt end of the awl 19 is extended to a distance beyond the pivot screw 15 so that when the awl is turned up inside the handle 2, the butt end of the awl shall project beyond the handle, as at 20. This butt end has a beveled edge and is adapted to be 100 105 110

used for a screw driver when the awl 19 is turned to the position shown in Fig. 1. The awl is held in either its closed or opened position of course by means of the spring 18 and the screw 15.

A scratch or round awl 21 has a flattened rear end 22 which is held to the flattened inner face of the handle 2 by means of a screw 23 and a washer 24. This scratch awl is 10 preferably round in cross section and tapers to its extremity. When it is desired to use the scratch or round awl, it is turned at right angles to the handle to which it is pivoted. Under ordinary circumstances, however, the round awl is held in parallel relation to the handle 2, the point of the awl having a slight engagement with the head 12 of the screw 11.

Attached to one of the handles 2 of the 20 pliers, and preferably rearward of the pivotal point thereof, is a guide box 25 which extends over the corresponding portion of the opposed plier handle. This guide box is composed of two opposed plates 26 and 27, 25 one of which plates, 27, is slotted longitudinally, as at 28.

29 designates an I-shaped slide gage mounted within the box and adapted to slide between the plates 26 and 27. A set screw 30 having a head 31 passes through the slit 28 and into the slide so that the slide is clamped into any adjusted position. Attached to the edge face of the plier handle by means of a screw 32 and a box washer 33 is a knife blade 34 having an edge 35 which is inclined toward the nose of the pliers. The plate 27 is extended somewhat and notched, as at 36, and the edge of the blade 35 projects into this notch 36. It will 40 be seen that the gage slide 29 is adapted to be adjusted longitudinally along the plates 26 and 27 and nearer to or farther from the knife blade 34 so as to permit laces of different widths to be cut, the laces being cut upon 45 the inclined edge of the blade.

It will be seen from Fig. 6 that the knife 34 is detachably connected to the guide by means of the clamp 33, and that the knife is held from any rotation under cutting 50 strain. This is secured by providing the lower plate 26 of the guide with the downwardly extending attaching flange 26^a which is in alinement with the notch 36. This attaching flange permits the guide to 55 be attached to the edge of the handle. The knife 34 in addition to having the inclined cutting edge 35 is cut away on its side as at 34^a to form a shoulder, this cut away portion being approximately the same length as 60 the length of the attaching flange 26^a. The clamping member 33 has the inwardly turned end flanges 35^a which embrace the knife and also embrace the edges of the attaching flange 26^a and fitting beneath the 65 shoulder on the knife 34. Thus when the

screw 32 is turned up the flanges of the clamp 33 will engage on each side of the attaching flange 26^a, will clamp the knife firmly in position and will prevent any rotation of the knife. At the same time the 70 construction permits the blade to be readily removed for grinding and new blades easily substituted at any time.

It will be seen that laces of different widths may be cut by moving the gage to 75 the desired position on the lace cutter, and that holes of different sizes can be made by the swage awl and leather punch, while laces may be threaded by means of the thong or lacing awl 10, the perforations of the lacing awl permitting the laces to be inserted through the awl and forced through the belt. To cut a lace with the lace cutter, the pliers are taken in the right hand and held horizontal, with their jaws from the 80 operator, and with the lace cutter up.

The strip of leather from which the lace is to be cut is held in the left hand and supported horizontally. The cutting blade of the lace cutter is inserted in a notch in the 90 leather, and the gage or slide 29 is adjusted against the edge of the leather. The leather is then drawn against the cutting edge of the knife by any suitable means, but preferably the instrument is drawn against lace, 95 and the lace will be cut out from the right side of the strip of leather as the operator faces it. The object of the slide 29 is to keep the lace of even width along the whole extent of the leather strip from which the lace 100 is being cut. This is accomplished by keeping the edge of the leather strip against the gage 29 while the leather is being drawn against the knife.

It will be seen that my invention makes 10 an extremely convenient implement for use in all the operations of repairing or replacing belts, and that the different members of the implement are so arranged and modified that they are all combined in one single 11 implement without one interfering with the operation of the other implements.

Having thus described the invention, what I claim is:—

1. An implement for cutting laces from a 11 leather strip including a handle, a guide supported on the handle and comprising parallel spaced plates connected at one end, one of the plates projecting beyond the other plate and being formed on its inside face 12 with a notch, a removable knife mounted upon the open end of the guide and having an inclined cutting edge, the apex of the knife resting in said notch, means for detachably securing the knife to the guide and 12 preventing a rotation of the knife, and a gage block slidably mounted in the guide and adjustable toward or from the knife.

2. An implement for cutting belt laces from a leather strip including a handle sub- 13

stantially rectangular in section, a guide supported on one face of the handle and comprising parallel spaced plates, one of the plates resting against the handle and having at its outer end an angularly bent attaching flange contacting with the side of the handle, the opposed plate extending beyond the face of the said attaching flange and being formed with a notch in its inside face alining with the face of the flange, a knife detachably mounted on the face of the flange, said knife having an inclined cutting edge, the apex of the cutting edge resting in said notch, means for detachably securing the knife to the face of the attaching flange and locking it against rotation, and a gage block slidably mounted in the guide and adjustable toward or from the knife.

3. An implement for cutting belt laces from a leather strip including a handle substantially rectangular in section, a guide supported on one face of the handle and comprising parallel spaced plates, one of the plates resting against the handle and having at its outer end an angularly bent attaching flange contacting with the side of the handle, the opposed plate extending beyond the face of said attaching flange and being formed with a notch in its inside face alining with the face of the flange, a clamp having inwardly extending marginal flanges fitting over the attaching flange, a screw passing through the clamp and flange and into the handle, a knife having an inclined cutting edge on its end and a projecting shoulder on one side extending over one of the flanges of the clamp when the knife is in place, a gage block shiftably disposed between the parallel plates of the guide, and

means for adjustably holding the gage block nearer to or farther from the knife.

4. An implement for cutting belt laces from a leather strip including a handle substantially rectangular in section, a guide supported on one face of the handle and comprising parallel spaced plates, one of the plates resting against the face of the handle and having at its outer end an angularly bent attaching flange contacting with the side of the handle, the opposed plate extending beyond the face of said attaching flange and being formed with a transverse notch on its inside face alining with the face of the flange, a knife mounted upon the face of the flange having an inclined upper end forming a cutting edge, the apex of said end extending into said notch, said knife being provided with a lateral shoulder, a clamp having oppositely disposed inwardly turned flanges adapted to embrace the knife below the shoulder and to embrace the attaching flange, a screw passing through the clamp, the knife and the attaching flange and entering the handle, a gage block slidably mounted between the parallel plates and having oppositely disposed parallel side pieces engaging with the edges of the plates, and an adjusting screw passing through a slot in one of said plates adapted to shift the gage block and hold it in any desired adjusted position.

In testimony whereof I affix my signature in presence of two witnesses.
